UNITED STATES PATENT OFFICE.

FRANK F. KAMP, JR., AND ROBERT K. GUNDY, OF LAWRENCE, PENNSYLVANIA.

METALLIC TIE AND RAIL-FASTENER.

No. 854,504.

Specification of Letters Patent.

Patented May 21, 1907.

Application filed March 25, 1907. Serial No. 364,281.

To all whom it may concern:

Be it known that we, FRANK F. KAMP, Jr., and ROBERT K. GUNDY, citizens of the United States of America, residing at Lawrence, in the county of Washington and State of Pennsylvania, have invented certain new and useful Improvements in Metallic Ties and Rail-Fasteners, of which the following is a specification, reference being had therein to the accompanying drawings.

This invention relates to metallic ties and rail fasteners, and the invention has for its primary object to provide a tie for supporting rails which will form a firm foundation or roadbed for a track.

Another object of this invention is the provision of novel means in connection with our improved tie for preventing the rails of a track from spreading or becoming vertically displaced with relation to the tie.

Our invention aims to prevent the numerous accidents in connection with railways due to the faulty construction of rail fasteners and road beds, and to this end, we have devised a tie that can be easily and quickly tamped to form a solid bearing for rails, and in connection with the tie, we use permanent outer rail fasteners and detachable inner rail fasteners, it being a well known fact that the stresses and strains of rolling stock passing over a track have a tendency to spread rails upon a tie. In using permanent fasteners upon the outer sides of the rails it will be impossible for the rails to spread.

With the above and other objects in view, which will more readily appear as the invention is better understood, the same consists in the novel construction, combination and arrangement of parts to be hereinafter more fully described and then specifically pointed out in the appended claims.

Referring to the drawing forming part of this specification, like numerals of reference designate corresponding parts throughout the several views, in which:

Figure 1 is a view of our improved tie and rail fasteners partly in elevation and partly in section, Fig. 2 is a plan of the tie illustrating a fastener securing a rail upon one end of the tie, Fig. 3 is a perspective view of the split key used in connection with the tie, Fig.

4 is a perspective view of a wedge-shaped fish bar forming part of our improved rail fastener, Fig. 5 is an enlarged perspective view of one end of the fish bar.

To put our invention into practice, we construct our improved tie of metal, the tie conforming in shape to the ordinary wooden tie. In forming the tie of metal we cut away the sides as at 1, 1 and provide the same with a longitudinally disposed bore 2 having its end terminating in the top of the tie, as at 3. The bore 2 serves two purposes namely to dispense with an expensive solid metallic tie and provide means whereby the tie can be tamped in a road bed. The bore 2 can be filled with ballast or similar material, which adds weight to the tie without incurring considerable expense. To drain the bore 2 we provide each end of the tie with openings 4.

The tie adjacent to each one of the bore openings is provided with an integral rail support or fastener 5 adapted to brace the outer side of a rail 6 mounted upon the tie.

The tie is also provided with tapering dove-tail grooves 7 provided at their smaller ends with openings 8, each opening branching to provide a triangular shaped block 9, the object of which will be presently described.

In the tapering dove-tail shaped grooves 7 are mounted tapering fish bars 10, said bars being dove tailed as at 11, to fit within the grooves 7. These bars are adapted to embrace the inner sides of the rail 6, and to assist in placing or removing the bars, we provide each end of the bar with an enlargement 12, to receive the blow of a hammer or similar instrument used in placing the bars in their respective grooves.

In connection with each bar, we use a key 14 said key being split as at 15. The keys are adapted to pass through openings 16 formed in the cut away ends 17 of the bars, said keys passing downwardly into the openings 8 and engaging the triangular blocks 9, where the key is split when being driven into the openings 16 and 8.

It will be apparent from the illustration of our invention that we have devised positive and reliable means for holding two rails upon a tie, and from the novel construction of the tie, it will be observed that the same is cast

from metal and forms a durable structure capable of withstanding the rough usage to which ties are ordinarily subjected.

It is obvious that such changes in the size, proportion and minor details of construction as are permissible by the appended claims, may be resorted to without departing from the spirit and scope of the invention.

What we claim and desire to secure by Letters Patent, is:—

1. In a metallic tie and rail fastener, the combination with rails, of a metal tie having a longitudinally disposed bore formed therein having its ends terminating at the top of said tie, said tie having openings formed therein to drain said bore, integral fasteners carried by the ends of said tie for bracing the outer sides of said rails, dove tail wedge-shaped fish bars detachably mounted upon the top of said tie and bracing the inner sides of said rails; said tie being formed with triangular shaped blocks, split keys adapted to

pass downwardly through said bars and engage said blocks and have their ends separated to lock said keys in said tie. 25

2. In a metallic tie and rail fastener, the combination with rails, of a metal tie having a longitudinally disposed bore formed therein, fasteners carried by said tie and bracing the outer sides of said rails, dove tail fasteners detachably mounted upon said tie to brace the inner sides of said rails, split keys adapted to pass downwardly through said fasteners to engage in said tie, and means carried within said tie for splitting the ends 30 of said keys.

In testimony whereof we affix our signatures in the presence of two witnesses:

FRANK F. KAMP, JR.
ROBERT K. GUNDY.
